(57) **CLAIM**

The ornamental design for a connector pull tab, as shown and described.

DESCRIPTION

FIG. 1 is a front, top and right perspective view of a connector pull tab showing my new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof; and,

FIG. 7 is a bottom plan view thereof.

Any broken lines shown in the drawings represent unclaimed environment and form no parts of the claimed design.
